Application June 2, 1939, Serial No. 277,012

13 Claims. (Cl. 82—1.1)

This invention relates to machines for resurfacing phonograph records, and more particularly to improvements in such machines for facilitating their use and for safeguarding the machines from such misuse as may result in damage to the machines. In some respects this invention is an improvement upon certain features disclosed in a copending application of Charles Huenlich, Serial No. 251,658, filed January 19, 1939, and entitled "Phonograph record resurfacing machines", which application is connected by common ownership with the present application.

Phonograph record resurfacing machines comprise a rotatable support for a record, usually in the form of a mandrel, a resurfacing tool settable into operative position relative to the record, and means for concurrently rotating the record support and feeding the tool along the record to cause a resurfacing, or a cutting away of a surface layer, of the record. In a properly performed record-resurfacing operation a cut is taken from the record of a depth just sufficient to completely obliterate the recordation on the record and in such a manner as to obtain a highly smooth record surface. In order to take a proper depth of cut and to obtain the degree of surface smoothness desired, a resurfacing tool of a delicate construction is employed. Careful handling of this tool is required to insure an accurate setting of the tool and to prevent damage to the tool or record.

It is an object of our invention to safeguard the tool and the record to be resurfaced from damage arising from misoperation of the machine.

It is another object of our invention to provide improved means to facilitate the normal operation of the machine.

It is another object of our invention to automatically stop the machine as an incident to a setting of the tool.

It is another object of our invention to provide means adapted to prevent the setting of the tool on a moving record.

Another object of our invention is to provide new and improved means operatively connecting the resurfacing tool with the control means of the machine so as both to facilitate the normal use of the machine and to safeguard the machine from damage arising from misuse of the machine.

Other and allied objects of our invention will more fully appear from the following description and the appended claims.

In the description of our invention reference is had to the accompanying drawings, of which:

Figure 1 is a top plan view of a phonograph record resurfacing machine in which our invention is incorporated;

Figure 2 is a vertical sectional view taken substantially along the line 2—2 of Figure 1;

Figure 3 is a fractional top plan view of the interlinkage means laterally dottedly shown in Figure 1; and

Figure 4 is a fractional top plan view of the tool-setting means showing details of the coupling of the resurfacing tool with the interlinkage means abovementioned.

Reference being had to the figures, there will be seen a phonograph record resurfacing machine of a form commonly used to resurface phonograph records of the type employed in dictating machines, comprising a base plate 1 having a left-hand upright standard 2, an intermediate 15 upright standard 3, right-hand upright standards 4 and 5, and an upright boss 6 directly to the right of the standard 5. Pivoted to the boss 6 is an endgate 7 biased into open position by a torsional spring 8 but normally held in closed 20 position, as shown in Figure 1, by an endgate bolt or latch 9 pivoted as at 10 to the right end portion 11 of a guide rail 12 extending laterally 25 along the front of the machine. The endgate 7 carries a conically pointed stud 13 which together 30 with a conically pointed stud 14, carried by the standard 2, form right and left thrust bearings for a shaft 15 extending laterally of the machine in parallel relation to the guide rail 12. The shaft 15 passes through an oversized hole 16 in 35 the intermediate standard 3, and is provided with a mandrel 17 for removably supporting a cylindrical record 18 to be resurfaced. To mount or remove a record from the mandrel 17, the endgate 7 is first opened to free the right end of the 40 mandrel; during the time the endgate is open the shaft 15 is intermediately supported by the intermediate standard 3 and is retained in engagement with the conical stud 14 by the contact of a collar 19, secured to the shaft by a screw 19', 45 with the left side of the intermediate standard 3.

Parallel to the shaft 15 and guide rail 12 is a rod 20 supported by the left and right standards 2 and 5. Slidably and tiltably mounted on the 50 rod 20 is a carriage 21 having a sleeve 22 embracing the rod. As shown in Figure 2 the carriage is provided with an arm 23 curved forwardly over the mandrel 17 and terminating in a shoe 23' which normally slidably rests on the guide 55

rail 12. The carriage is steadily moved or fed in a leftward direction across the mandrel (as between start and terminal positions at the right and left ends of the mandrel respectively) by a 5 feed screw 24 rotatably supported by the left and right standards 2 and 4. Secured to the carriage sleeve 22 by the screws 25 is a resilient and rearwardly extending arm 26 carrying a feed nut 27 which normally engages the underside of 10 the feed screw. When the carriage arm is tilted upwardly, as until a rearwardly and downwardly extending post 28 impinges against a laterally extending ridge 29 on the base plate (see Figure 2), the feed nut 27 is moved downwardly out of 15 engagement with the feed screw to permit the carriage to be manually moved, at will, across the mandrel. When the carriage arm 23 is, however, resting on the guide rail 12, the feed nut 27 is in engagement with the feed screw 24 to cause 20 the carriage to be fed along the mandrel by the rotation of the feed screw. In order that such feeding of the carriage will occur coincidentally with a rotation of the mandrel, the feed screw is provided with a pulley 30 which is coupled, as 25 by a belt not shown, to a pulley 31 on the mandrel shaft 15. In the operation of the machine the mandrel 17 and feed screw 24 are turned in a clockwise direction, the direction of thread on the feed screw being such as to then cause a 30 leftward feed of the carriage.

On the right side of the carriage there is an extension 32, square-shaped as viewed from the end, which substantially overlies the rod 20. The extension 32 carries a resurfacing tool 33 comprising a knife blade 34 mounted on a knife bar 35 which is slidably supported by the extension 32 for movement towards and away from the record. The means for setting the resurfacing tool into operative position—a position of the 35 tool in which the knife blade 34 engages the record—and for releasing the same may be of a well known construction such as is disclosed in Brown Patent No. 2,137,383, issued November 22, 1938, and entitled "Record shaving machine".

45 A tool-setting mechanism of the abovementioned type is sufficiently described in the present instance as follows: A cap 36 is slidably mounted on the extension 32, guided by a guide rod 37, and coupled to the knife bar 35 by a compression spring 38 coiled about the knife bar between the cap 36 and a shoulder 35' on the knife bar, this coupling serving to yieldably move the knife bar downwardly towards the record when the cap 36 is moved downwardly. When the cap 36 50 is moved upwardly the top thereof contacts a head 40 on the knife bar 35 to move the knife bar away from the record. The cap 36 is normally held in an upward position and the knife bar 35 is thereby normally held in a position 55 free of the record—the inoperative position of the tool—by a compression spring 39 coiled about the guide rod 37, the inoperative position of the knife bar or tool 33 being defined by the contact of a collar 41 on the bar 35 with the underside 60 of the extension 32. The setting of the tool 33 is controlled by a lever 42 pivoted on the right side of the extension 32 and having a short arm 43 which is coupled to the cap 36 by an angular link 44, the link being pivoted to the arm 42 65 by a pin 45 and to the cap 36 by a pivot screw 46. As the lever is swung forwardly in a counter-clockwise direction the cap 36 and knife bar 35 are moved downwardly, the tool being moved 70 into operative position relative to the record; in 75 the terminal movement of the lever a lock 47,

described in detail in the abovementioned Brown patent, is rendered operative to hold the tool in operative position, thereby completing the setting of the tool.

Such forward or setting movement of the lever 42 is limited to the position shown in Figure 2 by the impingement of the link 44 on the hub 42' of the lever. When the lever is in this most forward position the pin 45 is slightly past dead center with respect to the pivot axes of the lever 42 and the pivot screw 46. The upward biasing force exerted on the cap 36 then causes the lever 42 to be urged in a counter-clockwise direction—the direction in which the lever 42 is moved to set the tool—but movement of the lever in such direction is prevented by the contact of the link 44 with the hub 42'. Thus when the lever 42 reaches such limited position, the lever is releasably held there to maintain the tool in operative position. When the lever 42 is, however, tripped, or moved slightly in a clockwise direction, to return the pin 45 across the dead center line aforementioned, the lever 42 is returned and the cap 36 is moved upwardly, as by the spring 39, to render the lock 47 inoperative and there- 25 after to return the tool to inoperative position.

In the operation of resurfacing a record the carriage is first moved to bring the tool into a position overlying the record to permit the setting of the tool. This carriage movement is 30 effected by first tilting the carriage upwardly, to disengage the feed nut from the feed screw and to raise the tool away from the record, and then by manually moving the carriage into the position desired. Then the resurfacing tool is 35 set into operative position, the carriage manually returned to start position, and the machine started to cause mandrel rotation and a feeding of the carriage along the mandrel in a leftward direction. As the carriage is thus fed along the 40 mandrel a cut is taken from the record, the cut-away layer—commonly known as shaving chips—being carried by a chip-chute 48 downwardly through an opening 48' in the base plate.

The driving means for the machine—the means 45 for feeding the carriage and rotating the mandrel—may comprise a suitable electrical motor (not shown) which may be located beneath the base plate 1 and may be coupled to a pulley 49 on the mandrel shaft 15 by a belt (not shown) 50 which may pass through an opening 50 in the base plate. The starting and stopping of the motor may be controlled by a switch 53, preferably of the single-pole single-throw variety, which is mounted on the underside of the base 55 plate in the front right-hand portion thereof. The switch 53 has a forwardly extending arm 54, pivoted as at 54'; coupled to the arm 54 is a forwardly extending control lever 55, hereinafter described, which is pivoted to move leftwardly and rightwardly into respective "on" and "off" positions (the "on" position of the lever being shown in Figure 1) to effect the closing and opening of the switch.

The above described structure and mechanism 65 are common to record shaving machines heretofore manufactured and used, and form a part of the present invention only in so far as they are related to or combined with other mechanism hereinafter described.

In the use of a record resurfacing machine there may be accidentally performed manipulations on the machine which will result in a defective operation of the machine, if not in damage 70 to the machine and to the record to be resur- 75

faced. For example, an attempt may be made to set the tool while the record is in movement. This may cause considerable damage to the tool and record; in the least it would result in an inaccurate setting of the tool. As a further example, in resetting the tool on a newly mounted record, the carriage may be returned from its terminal position while the tool is yet in its previously set position. If the newly mounted record were of a greater diameter than the previously mounted record, such return of the carriage might result in a scraping of the tool on the record. This scraping would, however, be avoided if the tool were released from its previously set position before the carriage is returned. In accordance with our invention there is provided a new and improved means for facilitating the proper use of the machine, and particularly, in practice, for insuring against possible misoperations as above noted. This means comprises an interconnecting means between the control means for the machine and the resurfacing tool, which interconnecting means is arranged to effect the following results: If the tool is manually released from a set position or if an attempt is made to set the tool on the record, while the machine is in operation, the switch 53 is automatically thrown open to stop the machine; also, if the switch 53 is manually thrown open, while the tool is in a set position, the tool is automatically released from its set position, there being, however, no effect on the tool by the manual throwing of the switch 53 to closed condition to start the machine. The interconnecting means between the switch 53 and the resurfacing tool is closely related to the means which connects the switch 53 with the control arm 55; this latter means is now described.

The control lever 55 is provided with a vertical shaft 55' which passes through a boss 63 extending downwardly from the base plate. Secured to the lower end of the shaft 55', by a screw 64, is a forked member 65 having two rearwardly extending arms—a left arcuately-shaped arm 66 and a right arm 67 (see Figure 3)—of which the arm 66 terminates at a point to the left of the switch arm 54. When the control lever 55 is in its "off" position the switch arm 54 is retained in its leftward position—the position resulting in an "open" condition of the switch 53—by a tension spring 68 which urges the switch arm against a stop pin 69 on the switch. As the control lever 55 is moved leftwardly to "on" position the switch arm 54 is impinged upon by the arm 66 and thereby moved rightwardly to close the switch 53. When the switch 53 is placed into closed condition it is releasably maintained there by a latch 70 which catches onto the switch arm 54 to hold this arm in its rightward position, the latch 70 being pivoted by a shoulder screw 71 to a boss 72 extending down from the base plate and being biased by a tension spring 73 into operative position defined by the contact of the latch with a stop pin 74 on the base plate.

When the control lever 55 is moved rightwardly into "off" position the latch 70 is released from the switch arm 54 to permit the switch arm to be moved leftwardly, as by the spring 68, to effect the opening of the switch. To release the latch 70 there is pivoted on the arm 67 of the member 65, as at 75, a pawl 76. This pawl is urged, by a tension spring 77 connected between the pawl and an ear 65' on the member 65, in a clockwise direction into a position defined by the contact of a stop lug 76' on the pawl with the

right edge of the arm 67. Extending into the path described by the pawl 76 in the turning of the member 65 is a lug 78 which is turned down from a forwardly extending arm 79' of a lever 79 which is also pivoted on the shoulder screw 71 directly above the latch 70. The lever 79 has a leftwardly extending arm 79" provided with a lug 80 which is turned down at a point in front of the latch 70. As the control lever 55 is moved to "off" position the pawl 76 impinges against the lug 78 to turn the member 79 in a clockwise direction. This turning of the member 79 causes the latch 70 to be moved, by reason of its contact with the lug 80, into a released or inoperative position, thereby permitting the switch arm 54 to be snapped leftwardly by the spring 68 to effect the opening of the switch 53.

It is to be noted that when the latch 70 is released from the switch arm 54 it is not permitted to snap back into its operative position until the arm 54 nears the end of its leftward travel, the snapping back of the latch being controlled by the contact of a long angular face 70' on the nose of the pawl with the inner vertical edge 54" of the switch arm 54. This is done in order that the lug 78 will not be moved, by the latch 70, back into the path of the pawl 76 until the pawl 76 has been moved past the lug. When the switch is closed the arm 66 encounters the switch arm 54 and moves it rightwardly past the latch 70, the latch then snapping into operative position to releasably maintain the switch in its closed condition; also in the closing of the switch the pawl 76 moves past the lug 78, the pawl being turned against its biasing by its contact with the lug and then snapping back into its biased position.

With the above described mechanism, the machine is stopped by merely releasing the latch 70 from the switch arm 54. Thus to stop the machine both as an incident to the release of and to the setting of the resurfacing tool, we need only to cause these tool operations to release the latch 70. Reference being had to Figures 2 and 3, it will be seen that the means operatively connecting the latch 70 with the resurfacing tool is of a unitary character, comprising a bar 81 which extends laterally of the machine below the base plate along the rear edge of the opening 48'. The bar 81 is supported at its leftward and rightward ends by a pair of links 82 and 83 respectively pivotally connected to the bar by the pins 82' and 83' and to a pair of bosses 84 and 85 by the screws 84' and 85', the links 82 and 83 thus forming a pair of parallel-motion supports for the bar permitting the bar to move forwardly and rearwardly in parallel relation to the mandrel. The bar 81 is operatively connected with the latch 70 by means of a link 86 which is pivoted at one end thereof (as at 87) to the arm 79" of the member 79, and at the other end thereof (as at 88) to an arm 89 extending rightwardly from the link 83. The operative connection of the bar 81 to the resurfacing tool is made by means of a lever 90 (see Figure 2) which is pivoted on the right side of the carriage on a long shoulder screw 91. The lever 90 comprises a lower vertical portion 92 which slidably engages a slot 93 extending longitudinally of the bar 81, a central semi-circular portion 94 curved rearwardly about the longitudinal rod 20 and pivoted at its upper end on the shoulder screw 91 adjacently of the right side of the carriage, a bail portion 95 extending along the screw 91, and a pair of arms 96 and 97 respectively extending forwardly and upwardly 75

from the outer end of the bail portion 95. The arm 96 terminates at a point directly below the arm 43 of the tool-setting lever 42, while the arm 97 is provided with a cam 98 having upper and lower inclined faces 98' and 98'' which extend into the path of a pin 99 carried by an arm 100 on the tool-setting lever 42.

When the resurfacing tool is in a set position the lever 42 is in a forward position as is shown in Figure 2, the pin 99 being then directly above the cam face 98'. As the tool-setting lever is moved rearwardly to release the tool the pin 99 impinges against the cam face 98' and thereby moves the lever 90 in a clockwise direction, the pin 99 coming to rest in the position shown in dash-dot lines in Figure 2. As the lever 90 is so moved the bar 81 is moved forwardly because of the engagement of the portion 92 of the lever with the slot 93 in the bar, to cause the member 79 to be turned in a clockwise direction, this turning of the member 79 causing the latch 70 to be released from the switch arm 54 to permit the opening of the switch by the spring 68, as heretofore described. As the switch is opened the mechanism coupling the resurfacing tool with the switch is restored to its unoperated position for re-operation, as by the biasing of the latch 70. To prevent an inertia overthrow of this mechanism there is provided a stop 101 for limiting the counter-clockwise movement of the member 79.

As the tool-setting lever 42 is moved forwardly to set the tool into operative position the pin 99 impinges against the lower cam face 98'' and thereby again moves the lever 90 in a clockwise direction to cause the latch 70 to be released from the switch arm 54 in the same manner as in the release of the tool. Furthermore, when the switch 53 is manually thrown open by the control lever 55, the member 79 is turned, because of the contact of the pawl 76 with the lug 78 as heretofore described, to cause a forward movement of the bar 81 and a clockwise movement of the lever 90. If the tool is set when the lever 90 is so moved, the arm 96 of the lever 90 impinges against the underside of the arm 43 of the tool-setting lever 42 to trip the lever 42 from its set position, thereby causing the release of the tool. However, if the switch 53 is manually thrown open while the tool is set, the setting of the tool is not disturbed since the pawl 76 is adapted to move past the lug 78 without turning the member 79, as heretofore described.

Although we have herein shown and described one embodiment of our invention it will be understood that this embodiment is subject to many changes and modifications without departure from the scope of our invention, which we endeavor to express according to the following claims.

60. We claim:

1. In a phonograph record resurfacing machine having a record support: the combination of a resurfacing tool movable into and out of operative position relative to a record on said support; means for controlling the operation of the machine; and means, controlled by said resurfacing tool, for causing operation of said controlling means by the movement of said resurfacing tool into operative position.

70. 2. In a phonograph record resurfacing machine having a record support: the combination of a resurfacing tool settable into operative position relative to a record on said support; control means movable into "on" and "off" positions to start and stop the operation of the machine; and

means, operated as an incident to the setting of said tool, for causing said control means to be moved from "on" to "off" position.

3. In a phonograph record resurfacing machine having a record support: the combination of a resurfacing tool settable into an operative position relative to a record on said support; a circuit openable and closeable to control the operation of the machine; and means, controlled by said resurfacing tool and rendered effective incidental to the setting of said tool into operative position, for opening said circuit.

4. In a phonograph record resurfacing machine: the combination of a rotatable support for a record to be resurfaced; a resurfacing tool settable into operative position relative to a supported record; controllable rotating means for said record support; and means, operated by said tool as an incident to the act of setting the tool, for causing the stopping of said rotating means.

5. In a phonograph record resurfacing machine: the combination of a rotatable support for a record to be resurfaced; a resurfacing tool settable into operative position relative to a supported record and releasable therefrom; control means operable to start and stop rotation of said record support; and means, operated by said tool both as an incident to the setting of the tool into operative position and to the release of the tool therefrom, for causing operation of said control means to stop rotation of said record support.

6. In a phonograph record resurfacing machine having a record support: the combination of a resurfacing tool movable into and out of operative position relative to a record on said support; control means having "on" and "off" positions, for controlling the operation of the machine; and means, controlled by said tool, for moving said control means to "off" position by the movements of said tool into and out of operative position, respectively.

7. In a phonograph record resurfacing machine having a record support: the combination of a resurfacing tool mounted for movement relative to a record on said support; means movable to control the operation of the machine; and a unitary means, operatively connecting said resurfacing tool with said control means, for causing each to be moved as an incident of moving the other.

8. In a phonograph record resurfacing machine having a record support: the combination of a resurfacing tool settable into operative position relative to a record on said support and releasable therefrom; a control switch movable into "on" and "off" positions to start and stop the operation of the machine; and unitary means, operatively connecting said resurfacing tool with said control switch, for causing said control switch to be moved to "off" position by the release of said tool and said tool to be released by the moving of said control switch to "off" position.

9. In a phonograph record resurfacing machine having a record support: the combination of a resurfacing tool settable into operative position relative to a record on said support and releasable therefrom; a switch movable into "on" and "off" positions to control the operation of the machine; and means, operatively connecting said resurfacing tool with said control switch, for causing said control switch to be moved to "off" position by the setting of said tool into operative position and said tool to be released from operative position by the moving of said control switch to "off" position.

10. In a phonograph record resurfacing machine having a record support: the combination of a resurfacing tool settable into operative position relative to a record on said support and reusable therefrom; a control means for the machine movable into "on" and "off" positions; and means, operatively connecting said resurfacing tool with said control means, for causing said control means to be moved to "off" position both 10 by the setting of said tool into operative position and by the release of the tool from operative position and for further causing said tool to be automatically released from operative position as an incident to the moving of said control means 15 to "off" position.

11. In a phonograph record resurfacing machine having a record support: the combination of a resurfacing tool manipulatable towards and away from the record; control means for the machine having "on" and "off" positions and biased into "off" position; a latch for releasably holding said control means in "on" position; and means, operatively connecting said resurfacing 20 tool with said latch, for causing the unlatching 25

of said control means by a manipulation of said tool.

12. In a phonograph record resurfacing machine having a record support: the combination of a resurfacing tool manipulatable towards and away from the record; an openable and closeable control switch for the machine normally retained in open condition; a latch for releasably maintaining said switch in closed condition; and means for causing the release of said switch from closed condition by the respective manipulations of said resurfacing tool towards and away from the record. 10

13. In a phonograph record resurfacing machine having a record support: the combination of a resurfacing tool manipulated towards and away from the record; control means for the machine having "on" and "off" positions and biased into one of said positions; a latch for releasably holding said control means in the other 15 of said positions; and means for causing the release of said latch by a manipulation of said tool. 20
